Primary Examiner — Paula Allen Greene(74) *Attorney, Agent, or Firm* — Dragon Sun Law Firm,
PC; Jinggao Li; Nathaniel Perkins(57) **CLAIM**

The ornamental design for a wireless earphone, as shown and described.

DESCRIPTION

FIG. 1 is a front, right perspective view of a wireless earphone showing my new design;

FIG. 2 is a rear left perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a partially enlarged view of FIG. 1;

FIG. 10 is a partially enlarged view of FIG. 2; and,

FIG. 11 is a partially enlarged view of FIG. 3.

The broken lines around the wireless earphone in FIGS. 1, 2, and 3 and illustrated in enlarged views of FIGS. 9, 10, and 11 form no part of the claimed design.
